UNITED STATES PATENT OFFICE.

JAMES E. MAYHEW, OF BROOKLYN, NEW YORK.

GARMENT HANGER.

Application filed August 29, 1925. Serial No. 53,279. 60 65 70 75 80 85 90 95 100 105 110

This invention relates to garment hangers and has for its principal object to provide an improved garment hanger made from sheet material.

- 5 A further object of the invention is to provide an improved garment hanger made of sheet material which has no thin or sharp edges at those places where the garments are supported by the hanger.
- 10 The invention has for an additional object to provide a garment hanger which is simple in construction and inexpensive to manufacture.

15 Several embodiments of the invention are illustrated in the accompanying drawing, in which Fig. 1 is a perspective view of one form of garment hanger constructed in accordance with the invention.

20 Fig. 2 is a vertical transverse section taken on the line 2—2 of Fig. 1.

Fig. 3 is a vertical transverse section taken on the line 3—3 of Fig. 1.

25 Fig. 4 is a transverse section corresponding to that shown in Fig. 3, illustrating a different manner in which the extension flaps may be used.

Fig. 5 is a transverse section corresponding with the sections shown in Figs. 3 and 4, but illustrating a still further manner in 30 which the extension flaps may be used.

Fig. 6 is a perspective view of a further modified form of hanger, and

Fig. 7 is a development of the blank employed before it is folded to final form.

35 Referring first to Fig. 7, the blank from which one form of the hanger is made comprises a pair of triangular shaped portions 1 and 2, each of which has a substantial triangular shaped central opening 3. The portions 1 and 2 might conveniently be termed open center triangles. The portions 1 and 2 are joined along the line 4, so that this line forms the common base line for the two triangles. The term "joined" as just used

40 should not be restricted in its meaning to include only the connection or joining of two separate pieces, because the preferred manner of making the blank is to stamp the two triangular portions 1 and 2, from a single piece of sheet material, so that they are integrally joined or united along the line 4.

45 One of the two triangular shaped portions is provided along its sloping edges 5, with extension flaps 6. The blank is preferably creased along the lines 5 and each flap 6 is

preferably provided with a crease along the line 7.

50 One of the triangular portions of the blank is provided with an extension flap 8, on that portion 9 of the triangular part 60 which corresponds to the base of the triangle. The flap 8 is preferably demarcated by means of a crease formed in the blank along the line 10. The two apex portions, 11 and 12, of the blank are preferably shaped 65 in some such manner as shown in Fig. 7 in order to grip between them a supporting or suspending member as hereinafter described.

65 The blank described above may be formed from any suitable material such as thin 70 sheet metal, fibre board or the like, but preferably it is formed from inexpensive cardboard.

75 The blank is folded along the line 4 to bring the apex portions 11 and 12 into juxtaposition as shown in Fig. 1. The flaps 6 are also folded inwardly along the lines 5, and then downwardly along the lines 7. This will cause a portion 13 (Fig. 1) of each flap to lie in a plane which is substantially 80 at right angles to the plane of the hanger.

85 The downwardly extending portion 14 of each flap 6, resulting from the downward bending of the flap along the line 7, may be inserted between the two triangular portions of the hanger as in Figs. 1 and 3, or it may be allowed to overlap the adjacent edge of the other triangular portion as shown in Fig. 4. In either case the downwardly extending part 14 of the flap may be glued or 90 cemented to the adjacent edge portion of the other triangular part as indicated at 15 in Figs. 3 and 4, or it may be left free and uncemented. Fig. 5 indicates how the flap would appear if it overlaps the edge portion 95 of the other triangular part, but is left free and uncemented.

95 The flap 8 is also bent inwardly in a substantially horizontal plane as indicated in Fig. 1. 100

A hook or other suitable suspending or supporting member shown at 16, has its shank located between the two meeting apex portions 11 and 12 of the blank, which latter may be riveted together by means of suitable 105 fastening devices 17. If desired the parts 11 and 12 may be glued together to grip the shank of the hook 16 between them. The lower end of the shank of the hook may be headed as shown at 18, to prevent the shank 110

of the hook from pulling through the hanger.

A garment hanger of this particular shape, is often referred to as a combination garment hanger, and is usually employed for supporting a coat and trousers by hanging the coat over the sloping edges of the hanger and by supporting the trousers on the bottom cross piece of the hanger. The portion 10 13 of the flaps 6 form relatively wide supporting surfaces for the coat, and the horizontally projecting flap 8 forms a relatively wide supporting surface for the trousers. In this form of the device no sharp or narrow 15 edges are presented to the garments which might tend to form creases in them, in spite of the fact that the garment is made of sheet material. The flap 8 is of such width that it not only forms a relatively wide supporting 20 surface for the garment but it also serves to reinforce the hanger against lateral bending.

If desired the flaps 6 and 8 may be omitted, in which case the complete hanger would have the appearance indicated in Fig. 6. 25 This type of hanger has the advantage that it may be made out of relatively thin and inexpensive material, such as cardboard, the necessary strength and durability being furnished by forming the blank in such a manner that it may be folded together to produce the finished hanger shown in Fig. 6.

If it is not desired to have the garment hanger of the combination type, the central opening may be omitted in the form shown, 35 in Fig. 6 and the corresponding central opening in the form shown in Fig. 1, with the horizontally extending flap 8, may likewise be omitted.

The finished hanger may be printed, lithographed or colored if so desired. It may be advantageously used as an inexpensive advertising medium by printing suitable advertising matter upon it.

I claim:

45 1. A clothes hanger comprising a piece of

sheet material having two open center triangular portions united at their bases and folded together along their common base line, one of said triangular portions having flaps along those edges corresponding with the arms of the triangle, at least a portion of each flap being adapted to be folded into a plane substantially at right angles to the plane of the hanger and said flaps and the openings in the triangular portions being correlated so that said openings are unobstructed by the flaps. 50 55

2. A garment hanger comprising a piece of sheet material having two portions in the shape of open center triangles united at their bases and folded together along their common base line, one of said triangular portions having flaps along those edges corresponding with the arms of the triangle, at least a portion of each flap being adapted to be folded into a plane substantially at right angles to the plane of the hanger and one of 60 65 said triangular portions having a flap along the upper edge of its base portion adapted to be folded into a plane substantially at right angles to the plane of the hanger. 70

3. A garment hanger comprising a piece of sheet material having two portions in the shape of open center triangles united at their bases and folded together along their common base line, one of said triangular parts of the hanger having a flap along the upper edge of its base portion and adapted to be folded into a plane substantially at right angles to the plane of the hanger. 75 80

4. A garment hanger made of sheet material and having a central opening forming a bottom cross-piece adapted to support a garment and having an integral portion along the upper edge of said bottom cross piece 85 adapted to be bent into a plane substantially at right angles to the plane of the hanger.

In testimony whereof I affix my signature.

JAMES E. MAYHEW.
